United States Patent Office

Des. 192,364
Patented Mar. 13, 1962

192,364

HOLSTER

Earl J. Clark, Los Angeles, Calif., assignor to Buchheimer-Clark Leather Goods Corp., Los Angeles, Calif., a corporation of California

Filed Mar. 2, 1961, Ser. No. 64,123

Term of patent 14 years

(Cl. D30—1)

FIG. 3.

FIG. 1.

FIG. 2.

FIG. 4.

FIG. 5.

FIG. 6.

FIG. 1 is an elevational view of one side of a holster showing my new design;

FIG. 2 is an elevational view of the other side thereof;

FIG. 3 is a top plan view thereof;

FIG. 4 is a bottom plan view thereof;

FIG. 5 is an elevational view looking toward the open front portion of the holster; and

FIG. 6 is an elevational view looking toward the closed rear portion of the holster.

I claim:

The ornamental design for a holster, as shown.
